UNITED STATES PATENT OFFICE

112,894

DESIGN FOR A GAME BOARD

Bert J. Bratt, Chicago, Ill.

Application August 22, 1938, Serial No. 79,491

Term of patent 14 years

To all whom it may concern:

Be it known that I, Bert J. Bratt, a citizen of the United States, residing at Chicago, in the county of Cook and State of Illinois, have invented a new, original, and ornamental Design for a Game Board, of which the following is a specification, reference being had to the accompanying drawing, forming a part thereof.

Figure 1 of the drawing is a plan view of a game board showing my new design; and Figure 2 is an edge view thereof.

The drawing is lined to indicate contrasting colors.

I claim:

The ornamental design for a game board, substantially as shown and described.

BERT J. BRATT.
